UNITED STATES PATENT OFFICE.

AXEL W. FREDSON, OF EVERETT, MASSACHUSETTS.

TIDE-MOTOR.

SPECIFICATION forming part of Letters Patent No. 739,538, dated September 22, 1903.

Application filed July 18, 1903. Serial No. 166,161. (No model.)

To all whom it may concern:

Be it known that I, AXEL W. FREDSON, a citizen of the United States, residing in Everett, in the county of Middlesex and State of Massachusetts, have invented a new and useful improvement in Tide-Motors, of which the following is a specification.

This invention relates to that class of motors in which the ebb and flow of the tide are intended to furnish the power; and it consists in the novel construction and arrangement of parts hereinafter described, and illustrated in the accompanying drawings, in which—

Figure 1 represents a side elevation of my improved motor, the ground and wall being indicated in section. Fig. 2 is a cross vertical section taken centrally through the drum. Fig. 3 is a section of the drum, taken on line 3, Fig. 2. Fig. 4 is an enlarged detail, in end elevation, of the locking mechanism.

Similar characters of reference indicate corresponding parts.

a represents a portion of the ocean; *b*, the land, and *c* a wall built for the purpose of allowing the connection between the float and the part located on the land to be as short as possible.

d represents a frame supported on a suitable base *e*, sustained by the ground, said frame supporting pivotally at *f* a walking-beam *g* of suitable construction and preferably braced, as shown. The long arm of this lever or walking-beam extends toward and over the water and is pivoted at its outer end at *h* to the frame *i*, which is rigidly secured to a float *k* of any suitable construction. The short arm of the walking-beam is pivotally secured at *j* to the upright *l*, which is rigid with the upper cross-piece *m*, making a portion of a frame which consists of the cross-pieces *m*, the vertical stationary bar *n*, and the movable bar *p*. The bar *n* is provided with internal downwardly-extending rack-teeth, and the bar *p* is provided with internal upwardly-extending rack-teeth, said bar *p* extending through suitable slots or ways *r* in the cross-pieces *m* and being held up to its work by springs *s* in said slots bearing against said bar. Between the two bars and in engagement with the internal rack-teeth thereon is the ratchet-pinion *t*, supported by a suit-

able frame *u*, said ratchet-pinion being rigid with the shaft *v*, supported by the frame. Mounted on the same shaft, but not rigid therewith, is a drum *w*, containing a plurality of coiled springs *x*, one end of each of which is secured to the shaft and the other end to the drum. A ratchet-wheel *y* is rigidly connected with one end of the drum and is engaged by a pawl *z* on a horizontal spindle *l*, supported by the frame, the opposite end of said spindle being provided with a weighted arm *2*. Rigid on the drum is a driving-wheel *3*, which by means of a belt or other suitable contrivance transmits the power.

In practical operation as the tide rises and falls the float lifts and depresses the outer end of the walking-beam *g* and its inner end depresses and lifts the frame *m n p*, and whether said frame is depressed or lifted the pinion *t* turns in the same direction and communicates motion to the shaft *v*. This shaft operates to contract the springs until said springs communicate motion in the same direction to the spindle *w*, and hence to the driving-wheel *3*. Under ordinary circumstances, as in the day-time, these springs simply serve as connections between the shaft and drum; but at night, (or perhaps on other occasions,) when it may be found undesirable to utilize the power, the driving-wheel and drum may be stopped and locked by swinging the pawl *z* into engagement with the teeth on the ratchet-wheel *y*, and while the drum is thus locked the movement of the tide continues, by means of the mechanism *m n p t*, to slowly turn the shaft *v* and slowly wind the coiled springs *x*. Hence in the morning or whenever the locking-pawl *z* is swung out of engagement with the ratchet-wheel *y* the power thus stored by means of said spring is again applied to the drum and driving-wheel and utilized.

Having thus fully described my invention, what I claim, and desire to secure by Letters Patent, is—

1. In a tide-motor, a float; a walking-beam or lever pivotally supported on the land; the frame comprising the cross-pieces *m*, and the internal ratchet rack-bars *n*, *p*, said ratchet rack-bars being provided with reversely-pointing ratchet-teeth; the ratchet-pinion *t* suitably supported and in engagement with

both said rack-bars; a driving-wheel; and mechanism intermediate of the ratchet-pinion and the driving-wheel whereby motion is imparted to the latter, substantially as described.

2. In a tide-motor, a float; a walking-beam or lever pivotally supported on the land; the frame comprising the cross-pieces *m*, and the internal ratchet rack-bars *n*, *p*, said ratchet rack-bars being provided with reversely-pointing ratchet-teeth; the ratchet-pinion *t* suitably supported and in engagement with both said rack-bars, said rack-bars being held normally in engagement with the pinion by suitable springs; a driving-wheel; and mechanism intermediate of the ratchet-pinion and the driving-wheel whereby motion is imparted to the latter, substantially as set forth.

3. In a tide-motor, a float; a walking-beam or lever pivotally supported on the land; the frame comprising the reverse ratchet rack-bars *n*, *p*; a shaft; a ratchet-pinion rigid on said shaft and in engagement with said rack-bars; a drum mounted on the shaft; springs *x* within the drum and connected at one end therewith and at the other end with the shaft; a driving-wheel rigid with the drum; and mechanism for locking said drum, substantially as and for the purpose described.

In testimony whereof I have signed my name to this specification in the presence of two subscribing witnesses.

AXEL W. FREDSON.
